US00D743375S

(12) **United States Design Patent**
Lee

(10) **Patent No.:** US D743,375 S
(45) **Date of Patent:** ** Nov. 17, 2015

(54) **SPEAKER**

(71) Applicant: **Samsung Electronics Co., Ltd.**, Suwon-Si, Gyeonggi-do (KR)

(72) Inventor: **Gil-Jae Lee**, Seocho-gu (KR)

(73) Assignee: **Samsung Electronics Co., Ltd.**, Suwon-Si (KR)

(**) Term: **14 Years**

(21) Appl. No.: **29/461,471**

(22) Filed: **Jul. 23, 2013**

Related U.S. Application Data

(63) Continuation-in-part of application No. 29/431,755, filed on Sep. 11, 2012, now Pat. No. Des. 687,813.

LLP

(57) **CLAIM**

The ornamental design for a speaker, as shown and described.

DESCRIPTION

FIG. 1 is a top front perspective view of a speaker showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrating portions of the speaker are for environmental purposes only and form no part of the claimed design.

1 Claim, 4 Drawing Sheets
